Leslie M. Sheridan, 1300 Chicago St.,
Butte, Mont. 59701

Filed Mar. 14, 1966, Ser. No. 1,450

Term of patent 14 years

(Cl. D48—23)

FIG. 1

FIG. 2

FIG. 1 is an end elevation view of one end of a fluorescent lighting fixture, showing my new design therefor, and showing in phantom lines two fluorescent lamps attached to such fixture; and

FIG. 2 is a side elevation view of the fluorescent lighting fixture of FIG. 1, showing additional features of my new design.

The dominant features of my design reside in the portions shown in full lines.

I claim:

The ornamental design for a fluorescent lighting fixture, as shown and described.
